UNITED STATES PATENT OFFICE.

ARNOLD BOSSHARD, OF ARBON, SWITZERLAND, ASSIGNOR TO THE FIRM OF AKTIEN-
GESELLSCHAFT ARNOLD B. HEINE & CO., OF ARBON, SWITZERLAND.

APPLIANCE FOR SEVERING EMBROIDERED WEB.

No. 878,111.

Specification of Letters Patent.

Patented Feb. 4, 1908.

Application filed February 4, 1907. Serial No. 355,714.

To all whom it may concern:

Be it known that I, ARNOLD BOSSHARD, a citizen of the Republic of Switzerland, residing at Arbon, in Switzerland, have invented 5 certain new and useful Improvements in Appliances for Severing Embroidered Web; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 In making embroidered strips, insertions, bands with festoons, etc., by machinery, the usual practice is to embroider a succession of rows of the pattern on a common web of fabric. After completion of the embroidering 20 the various separate embroidered pattern-rows are separated from each other by the web being cut through by hand with a pair of scissors, along the dividing-line, the rows being thus detached in succession.

25 According to the present invention this tedious operation is obviated by the employment of an appliance, whereby on the dividing-lines of all the various pattern-rows the web is simultaneously partially destroyed by 30 being corroded away.

The severance is effected by the provision of tubular arms with nozzles above the web, in the spaces between the pattern-rows, which nozzles communicate with a corroding fluid 35 feed pipe and are borne by spring pressure against the edge of the embroidery at the dividing-lines of each pattern-row. When, therefore, the web travels forward the nozzles rub against the edges of the embroidered 40 pattern and thus deposit a very thin line of corrosive fluid along the parts at which the scissors were formerly applied, so that when the web subsequently passes over drying cylinders the rows are detached owing to the carbonizing action at the said parts.

One form of construction of the new appliance is shown in the accompanying drawing, in which

Figure 1 is a vertical section, Fig. 2 a plan, 50 Fig. 3 shows a severing device in side elevation, Fig. 4 the same in front elevation, Fig. 5 a vertical section and Fig. 6 a plan partly in horizontal section, and Fig. 7, is an enlarged

section showing the relation of the collar to the liquid supply chamber and suction chamber. 55

1 is the web of fabric which has been embroidered with the pattern-rows *a-i* (Fig. 2) and can be conducted over a table 2 in the direction of the arrow. 60

3 is a beam located transversely to the table and supported in uprights 4 in such manner that it can be vertically adjusted. Near its two ends the cross beam 3 is provided with vertical racks 5 with which mesh pinions 6 65 mounted on a shaft 7 that is supported in bearings on the uprights 4 and at one end of which shaft a crank handle 8 is provided (Fig. 4). This shaft is also furnished in well-known manner with a device (not shown in the drawing) whereby the crank 8 can be held in its various positions. To the cross beam 3 there are also secured opposite the space between the pattern-rows, carriers 9 which embrace the beam 3, but leave a free 75 space above and below it, so that they may be vertically moved. These carriers are fixed by means of set screws 10 passing through the carriers. In the carriers there engage vertical slides 11, which can be adjusted vertically by means of screw spindles 12. These slides each support a cylinder 13, through which there loosely passes a pipe 14, bent below so as to constitute a tubular arm 15, provided with a nozzle 16. Within the 80 cylinder is a spiral spring (Fig. 5) one end of which is secured to the cylinder at *a'* and the other end to the head *a* in which pipe 14 is secured, in such manner that it has always the tendency to turn the tubular arm 15 in 90 the direction of the arrow Fig. 6. The head *a* or top of the cylinder 13 is frictionally held in upper split end 13^a of the cylinder. Screwed into this head is a box *b* in the lower end of which the pipe 14 is rigidly secured 95 and this box *b* being threaded may be rigidly connected to the head *a* and partake of its movements. In the upper end of the box *b* is screwed a threaded gland *c* serving to secure the lower end of pipe 14^a to the box *b* 100 said pipe 14^a being of yielding material.

20 is a feed pipe for a corrosive liquid. This pipe is divided by a partition 17 into two chambers 18, 19, of which the latter communicates with a corrosive fluid reservoir (not shown in the drawing), while the 105

chamber 18 is connected with a suction device (likewise not illustrated). Above the carriers 9 collars 21 are provided on the pipe 20, each collar having a nipple with passage 22 (Fig. 7), into which the upper end of pipe 14^a fits. By turning the collar 21 on pipe 20 the passage 22 can be caused to communicate either with the aperture 23 leading to the chamber 18 on one side of the partition 17 or the aperture 24 through the pipe to the chamber 19 on the other side of the partition. To each carrier 9 is affixed a rod 25, the top of which has a loop 25^a that engages the collar 21 in such wise that when the carrier 9 moves upward, the rod 25 also moves up and the collar 21 is rotated on the pipe 20 to bring the pipe 14^a into register with the hole 23 of the suction chamber 18.

Above the cross beam 3 an eccentric 26 is located in each carrier 9, actuated from without by means of a hand wheel 27 for the purpose of moving the individual carriers into either of their positions. A and B are drying cylinders.

The operation of the appliance is as follows: The tubular arms 15 with their nozzles 16 are so adjusted that each nozzle (Fig. 6) presses against the edge 28 of the embroidery of its pattern-row, that is, above the dividing-line 29. When the web 1 travels in the direction of the arrow (Figs. 1 and 2) a thin stream of corrosive fluid flows along the dividing-line, and this liquid, on the web passing the drying cylinders A and B and owing to the carbonizing action of the latter, eats away the web fabric 1 along the line of demarcation and thus causes severance of the pattern-rows from each other. The spring in the cylinder 13 tends to rotate the pipe 14 and arm 15 and urges the nozzle against the relief embroidery so as always to follow the contour of the pattern-row.

By means of the crank handle 8 all the carriers 9, and therefore all the nozzles 16, can be raised simultaneously and thus brought out of action by reason of the beam 3 that carries them being raised while at the same time by means of the rods 25 all the pipes 14^a will be cut off from the corrosive fluid feed pipe and brought into communication with the suction pipe. The corrosive fluid remaining in the pipe 14 is thus sucked back, so that it can no longer flow from the nozzle 16.

By loosening the set screw 10 and then rotating the eccentric 26 by the hand wheel 27, each individual carrier 9 can be raised and thus brought out of action, the pipe 14^a at the same time being brought into communication with the suction chamber 18, to withdraw the corrosive liquid from the pipe 14.

I claim:—

1. In an embroidered web severing appliance, in combination, a plurality of spring

controlled tubular arms provided with nozzles which bear against the edge of the embroidery of each pattern row, means located above the web for supporting the nozzle pipes, and means for feeding corrosive fluid to the nozzles, substantially as described. 70

2. In an embroidered web severing appliance, in combination, a plurality of corrosive fluid feed pipes constituting tubular arms provided with nozzles which bear against the edge of the embroidery of each pattern-row, a cylinder through which each pipe passes, a coiled spring within the cylinder attached at one end to the latter and at the other end to the pipe, a carrier to which the cylinder is vertically adjustable and a beam extending across the web and supporting all the carriers in common, substantially as described. 75 80

3. In an embroidered web severing appliance, in combination, a plurality of corrosive fluid feed pipes constituting tubular arms provided with nozzles which bear against the edge of the embroidery of each pattern-row, a cylinder through which each pipe passes, a coiled spring within the cylinder attached at one end to the latter and at the other end to the pipe, a perforated carrier to which the cylinder is vertically adjustable, a beam extending across the web and passing through 90 and supporting all the carriers, an eccentric located in each carrier and bearing on the beam, and means for operating the eccentric, substantially as described. 95

4. In an embroidered web severing appliance, in combination, a plurality of corrosive fluid feed pipes constituting tubular arms provided with nozzles which bear against the edge of the embroidery of each pattern-row, a cylinder through which each pipe passes, a coiled spring within the cylinder attached at one end to the latter and at the other end to the pipe, a carrier to which the cylinder is vertically adjustable, a racked beam extending across the web and supporting all the carriers in common, a pinion shaft, mounted parallel with the beam and engaging the racked portion thereof, and a crank for rotating the shaft, substantially as described. 100 105 110

5. In an embroidered web severing appliance, in combination, a plurality of pipes constituting tubular arms provided with nozzles which bear against the edge of the embroidery of each pattern-row, means located above the web for supporting the nozzle pipes, a corrosive fluid supply pipe feeding all the nozzle pipes in common and divided longitudinally into two perforated chambers, and perforated collars turning on the supply pipe, each controlling one aperture of each supply pipe chamber and each communicating with one of the nozzle pipes, substantially as described. 115 120 125

6. In an embroidered web severing appliance, in combination, a plurality of pipes 130

constituting tubular arms provided with nozzles which bear against the edge of the embroidery of each pattern-row, a carrier supporting each nozzle pipe, a corrosive fluid supply pipe feeding all the nozzle pipes in common and divided longitudinally into two perforated chambers, perforated collars turning on the supply pipe, each controlling one aperture of each supply pipe chamber and each communicating with one of the nozzle pipes, and means connecting each collar with one of the carriers, whereby on the latter rising the collar is turned, substantially as described.

15 7. In an embroidered web severing appliance, the combination with a plurality of tubular arms each provided with a nozzle and means to urge the arms to keep the nozzles against the edge of the embroidery, of 20 means to supply corrosive fluid to the tubular arms, means to simultaneously raise the

arms from the embroidered web and means to independently raise them from the web.

8. In an embroidered web severing appliance, the combination with a plurality of 25 tubular arms each provided with a nozzle and means to urge the arms to keep the nozzles against the edge of the embroidery; of means to supply corrosive fluid to the tubular arms, means to simultaneously raise 30 the arms from the embroidered web, means to independently raise the arms from the web and means to vertically and independently adjust each arm.

In testimony that I claim the foregoing as 35 my invention, I have signed my name in presence of two subscribing witnesses.

ARNOLD BOSSHARD.
